UNITED STATES PATENT OFFICE

107,970

DESIGN FOR A WORKSTAND OR THE LIKE

Edward M. Pfauser, Elm Grove, Wis., assignor to Blackhawk Mfg. Co., Milwaukee, Wis., a corporation of Wisconsin

Application May 10, 1937, Serial No. 69,285

Term of patent 7 years

To all whom it may concern:—

Be it known that I, Edward M. Pfauser, a citizen of the United States and a resident of Elm Grove, in the county of Waukesha and State of Wisconsin, have invented a new, original, and ornamental Design for a Workstand or the like, of which the following is a specification, reference being had to the accompanying drawing, forming a part thereof.

In the drawing,

I claim:

The ornamental design for a workstand or the like, as shown.

EDWARD M. PFAUSER.
